OIL BURNER SUCTION DRAFT CONTROL

Robert T. Smith, Baltimore, Md., assignor to
Sherwood Brothers, Inc., a corporation of
Maryland

Application April 19, 1937, Serial No. 137,704

2 Claims. (Cl. 158—28)

The invention relates to oil burners and particularly to the automatic control of the fan draft or primary air whereby a single adjustment of the draft control to the quantity of oil fed from the nozzle effects automatic regulation of the draft, giving exactly the right amount of primary air to support the combustion at all times. The control of the invention further compensates for the fluctuations of the fan, eliminating the pulsations of the flame which are partly or wholly due to such fluctuations. These pulsations are one of the sources of noise in oil burner operation and tend to reduce efficiency. While these incidents to oil burner operation have been generally recognized as objectionable, their correction has not been previously accomplished in a satisfactory manner.

The apparatus has the further advantage that it provides increased capacity of adjustment of the draft control within a relatively small space, contributing to the compactness of the apparatus and avoiding the necessity for a spring or a long projecting counterweight lever.

The apparatus of the invention in the form in which it has been practiced includes a suction chamber on the intake side of the fan, the admission of air to which is controlled by a balanced shutter which determines the air supply to the chamber and to the fan. In this way the fluctuations of the fan are compensated and the pulsation of the flame eliminated or reduced. This chamber preferably encloses the oil pump and has the effect of reducing the noise transmitted to the dwelling apartment heated by the apparatus, both as to the noise of the oil pump and that resulting from the fan, which are important elements contributing to the noisy operation which has been found to offer resistance in connection with the sale of oil burners.

In the accompanying drawings, I have illustrated a draft control and suction chamber embodying the features of the invention together with so much of an oil burner apparatus as is believed to be necessary to a full understanding of the invention and the manner of applying and operating the same.

In the drawings:

Figure 1 is an elevation of an oil burner assembly looking at the same from the rear; i. e., in the direction in which the oil is projected into the furnace, showing the suction chamber, the automatic suction control shutter and counterweight.

Figure 2 is a view looking at the same from

the left in Figure 1, the burner tube being broken away.

Figure 3 is a fragmentary section on the plane of the axis of the suction chamber showing the details of the draft control, the weight being broken away and shown partly in elevation and the weight and shutter being shown in dotted lines in an open position.

Figure 4 is a section on the line 4—4 in Figure 1.

Figure 5 is an elevation corresponding to Figure 3, showing a modified form of draft control.

Figure 6 is a fragmentary section of the nozzle and of the burner end of the tube.

Referring to the drawings by numerals, each of which is used to indicate the same or similar parts in the different figures, the construction shown, which is regarded as the preferred form, considerable variation as to detail being contemplated, comprises a burner tube 1, fan housing 2, a fan or rotary blower 3 which is preferably of the Sirocco type, an electric motor 4 which is supported on the fan casing with its axis in line with the axis of the fan, the motor shaft 5 being connected to the fan to drive the same. The fan 3, as shown, is of the type having a central feed and peripheral or tangential discharge, the fan draft being discharged directly into the burner tube 1.

The fan casing 2, as shown, has a central opening on the left side as seen in Figure 1 at 7, and the suction chamber 8 shown in elevation in Figure 1 is secured to the fan casing in and around the opening 7.

In the form shown, the throat 9 of the suction chamber 8 is provided with a tapered discharge mouth 10 which projects into the fan housing 2 and has a circular outer peripheral seating surface 11 which fits in the opening 7, the throat 9 having a circular flange at 12 at the outer side of the seat 11. The flange 12 rests upon and fits the outer flat surface of a circular boss 14 which surrounds the opening 7, being formed on the fan casing 2.

The seating surface 11, the inner surface of the opening 7, and the contacting surfaces of the flange 12 and the boss 14 are preferably finished to make a good contact; and the suction chamber 8, or more particularly the throat 9 thereof, is secured to the boss 14 in any suitable manner, as by means of bolts 15.

The suction chamber 8, as shown, is formed in two sections—16 and 17 which are lapped and joined in any suitable manner, as by rabbeted joint 19, being secured together by means of screws 18 passing through the overlapping por-

tions of the two sections at the joint 19. The main section 16 of the chamber is shown as slotted longitudinally at 20 adjacent the joint, the slot having an open end at the outer edge 21 of the main section 16 of the casing and being for a purpose to be hereinafter described.

The section 17 of the suction chamber 8 in the form shown is provided with a pump supporting ring 22 adjacent the throat, the said ring having its axis in line with the fan axis. The ring 22 is shown as formed integrally with the casing wall, being supported by radial struts 24 which may have strengthening webs 25. Between the struts 24 there are sector shaped openings 26 for the suction air as it leaves the chamber 8 and passes through the throat 9 and mouth 10 to the intake of the fan 3.

Figure 1 also shows the oil pump 27 which is supported by means of its bearing boss 28 which fits in the ring 22, the pump shown being of the gear type driven by the shaft 5 which is connected to the center of the fan 3 and is driven by the motor 4.

The oil is passed from the pump to the burner tube by way of the pump discharge pipe 29, being fed to the pump by way of the suction pipe 30. Both pipes 29 and 30 are passed through the plate 33 which covers slot 20, being secured to the outside of the casing in any suitable manner, as by means of bolts 34. Suction pipe 30 is connected to the source of oil supply not shown.

When the section 16 of the casing is removed as hereinafter described, as for adjustment of the oil pump or cleaning the strainer, the bolts 34 which hold the plate 33 in place are removed and the slot 20 releases the pipes as the section 16 is withdrawn.

The section 16 of the suction chamber is provided at its end remote from the fan housing with an opening 35 which is preferably in line with the fan axis and concentric therewith, the opening 35 being preferably circular. This location of the opening is subject to change, as is also the fan and arrangement of the suction chamber.

As shown, the opening 35 is provided with an internal peripheral flange 36 and a balanced suction draft shutter 37 is pivotally mounted in the opening, being supported by and on a horizontal pivot 38 which is seated at its ends in the walls of the opening 35 as best shown in Figure 2 which shows adjustable bearing members 39 that engage the ends of the pivot, being threaded in openings 40 to provide for taking up on the bearing.

Important features of the invention relate to the provision of the balanced shutter 37, giving a balanced control of the suction air with means for adjusting the same to the quantity of oil fed from the nozzle, whereby the primary air is automatically regulated to the supply of oil fed from the nozzle so that a single adjustment of the air supply for any particular adjustment of the fuel serves to maintain constant proportions of the mixture of oil and air as thus adjusted, and the balanced shutter, together with the suction chamber, has the further important effect of compensating for fluctuations of the fan, maintaining these proportions and further overcoming the tendency to pulsation of the flame with the accompanying noise and loss of efficiency. Except for its compensating action in connection with fan fluctuations, the position of

the shutter is constant for each adjustment of the control.

In the form shown, the shutter 37 is counterbalanced by means of a weight 45 which avoids the variation of tension and consequent loss of adjustment due to a spring control.

The weight 45 in the preferred construction shown is in the form of a short cylindrical cup. As shown, the weight is provided with an adjusting screw 46 which is arranged in line of 10 the axis of the cup, having its end 47 secured in the bottom of the cup at the center, the screw 46 being for most of its length inside the cup and concentric with the walls 48 thereof.

The screw 46 in the form of the invention 15 shown provides an adjustment of the weight 45 in the direction of its axis, being threadedly engaged with a hub 49 through which the screw is threaded in the direction of a diameter of the hub. The hub 49 is in turn pivotally mounted 20 at 56 between the arms 50 of a bracket 51 shown as supported on the outer section 16 of the suction chamber 8 and preferably on the boss 52 which surrounds the shutter opening 35. Preferably the bracket is located at the top center 25 above the opening 35 and projecting outwardly beyond the opening.

In the form shown, the hub 49 has a substantially radial arm 53 which is rounded at its end at 54 or otherwise adapted to engage the outer surface of the shutter 37, preferably near the top edge of the same in the closed position of the shutter and well above the shutter pivot 38. In this position of the parts, the arm 53 is inclined downwardly and toward the shutter 35 at an angle of approximately 45 degrees with the horizontal, so that as the bottom of the shutter swings toward the fan the center of gravity of the weight is raised, thus opposing the downward tendency of the weight due to gravity to 40 the tendency of the shutter to open in response to the suction of the fan, it being apparent that the center of the shutter area and hence the center of effort of the suction as applied to the shutter tending to open the same, is well below the pivot 38, and the contact of the lever 53 with the shutter at 54 is above the pivot. It is essential that the moment of the downward tendency of the weight be applied to the shutter in opposition to the moment of the suction as applied to said shutter, both moments being taken about the pivot 38 as a center. It is also an important element contributing to the useful operation of the device that the thrust of the suction against the shutter is gradually reduced 45 as the shutter opens, providing for balancing in a certain position determined by the lever arm of the weight and the degree of suction which is constant except for slight fluctuations compensated by the shutter.

It should be noted in this connection that the flange 36 which acts as a stop to locate the shutter in the position in which it closes the opening 35 is discontinued at 36' just below the pivot 38, permitting the shutter to swing from closed to open position. 55

It is of interest as contributing to the compactness of the apparatus by providing a conveniently short adjustment of the balance weight 45, that this weight to the best advantage is 70 provided with a self-counterbalancing feature which in the form shown is due to the cup shape of the weight 45 as described with the axially-arranged adjusting screw or other adjustment 46, the pivot 56 being adjustable within the cup 75

so that the center of gravity of the weight 45 can be adjusted in close proximity to the pivot. The walls 48 of the cup near the rim 55 and on the righthand side of the center of gravity in Figure 1 have, in certain positions when this rim portion is on the opposite side of the pivot from the center of gravity, a counterbalancing effect as to the weight. With this arrangement in the positions referred to where the center of gravity is near the pivot 56, a slight adjustment of the weight in either direction due to the counterbalancing effect of the rim portion 45 gives a relatively considerable change of the moment of the weight about the pivot 56 and a consequently considerable change of the counterbalancing effect of the weight on the shutter 37 and a corresponding change of the balanced position of the shutter.

In the form shown, this adjustment is performed by rotating the weight 45 and thus turning the screw 46 relatively to the hub 49, moving the weight in the direction of the axis of the screw and in a radial direction as to the hub 49 and the pivot 56. The weight may be otherwise arranged to give a counterbalancing effect and a self-counterbalancing effect which is of great advantage in giving a short adjustment from wide open to slightly open positions of the shutter.

In Figure 5, I have shown a modified form of counterbalance weight 45' which is provided with a counterbalancing ring 60 fitted to the outside of a cylindrical weight and capable of adjustment in the direction of the axis of the weight and the diameter of the pivot 56 whereby the self-counterbalancing effect referred to may be considerably increased without any increase of the over-all dimensions of the weight lever in the direction of the axis of the fan. It will be understood that other methods of changing the position of the center of gravity of the weight may be employed. The ring 60 may be used either to partially counterbalance the weight or to increase its moment about pivot 56, depending upon its relation to the center of gravity of the weight.

In order to increase the sound-deadening effect of the chamber, both as to the operation of the fan and the pump and any noise which may result from the flame, the suction chamber 8 has been shown as provided with a lining 58 of felt or similar material, and it will also be noted that in order to give access to the pump bearing 59, the throat 9 has been slotted at 63 to admit a wrench or key and this slot is provided with a removable cover 64.

In operation, the quantity of oil discharged from the fuel nozzle 65, within the burner tube 1, having been regulated either by changing the size of the nozzle or adjusting the pump valve 24' to give the pre-determined consumption of oil, the burner being started, the counterweight 45 is adjusted by the service man to cause the shutter 37 which is opened in response to the suction of the fan, to admit exactly the right quantity of air to give the most efficient combustion. When this adjustment has been attained, the screw 66 seated in the hub 49 and bearing on the weight-adjusting screw 46, which is also the lever arm, is tightened to hold the adjustment, the apparatus being thus placed in condition to run for an indefinite period with-

out further adjustment. In the operation of the burner, the shutter 37 is automatically opened to balanced position by the suction of the fan and held open during operation to just the right degree, which is constant in the absence of fluctuations of the fan, giving exactly the quantity of air necessary to support combustion most efficiently, as determined by the service man. If the oil supply is changed, the adjustment of the counterweight is changed, giving a different shutter opening adapted to admit the right amount of air for the new adjustment of the oil supply. In case of fluctuations of the fan, it is found that to such fluctuations the shutter responds with a relatively slow equalizing effect which breaks down the tendency to pulsations of the flame, giving uniform and quiet combustion. The motion of the shutter at these times is slight, and when the burner stops it closes.

The suction chamber 8 is found to afford important assistance in and to the equalizing effect of the balanced shutter by providing a sufficient volume of air between the shutter and the fan to assist in the dampening effect on the fan fluctuations already referred to; and it is also of importance that, the oil pump and the fan suction being thus enclosed, the noise which is transmitted to the apartment heated by the burner is greatly reduced and this reduction of noise is assisted by the provision of the felt or similar lining indicated at 58.

I have thus described an oil burner suction control embodying the features of my invention in the preferred form, the description being specific and in detail in order that the manner of constructing, applying, operating and using the same may be fully understood; however, the specific terms herein are used descriptively rather than in a limiting sense, the scope of the invention being defined in the claims.

What I claim as new and desire to secure by Letters Patent is:

1. In an oil burning apparatus comprising a rotary air blower, a housing encasing said blower, a motor located adjacent one side of said housing for operating said blower, said blower housing having an air inlet through the opposite side thereof and adjacent the axis of said blower, a muffling chamber supported about and outwardly from said air inlet, an opening in the opposite end of said casing, an oil force pump wholly located within said chamber and lying between the said opening and the air inlet to said blower housing, and means for receiving the air from said blower and conveying the same to a combustion chamber.

2. In an oil burning apparatus comprising a rotary air blower, a housing encasing said blower, a motor located adjacent one side of said housing for operating said blower, said blower housing having an air inlet through the opposite side thereof and adjacent the axis of said blower, a muffling chamber about and outwardly from said air inlet, an opening in the opposite end of said casing, means for automatically regulating the size of said opening, an oil force pump wholly located within said casing and lying between the said opening and the air inlet to said blower housing, and means for receiving the air from said blower and conveying the same to a combustion chamber.

ROBERT T. SMITH.
